[57] CLAIM

The ornamental design for a weigh scale, as shown.

DESCRIPTION

FIG. 1 is a top, front and left side perspective view of a weigh scale showing our new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view;

FIG. 8 is a top, front and left side perspective view, shown with the weighing pan inverted on the scale's top surface;

FIG. 9 is a front elevational view;

FIG. 10 is a rear elevational view;

FIG. 11 is a left side elevational view;

FIG. 12 is a right side elevational view;

FIG. 13 is a top plan view; and,

FIG. 14 is a bottom plan view thereof.
